UNITED STATES PATENT OFFICE.

CHARLES PARTINGTON, OF CINCINNATI, OHIO, ASSIGNOR TO THE CINCINNATI FROG & SWITCH COMPANY, OF CINCINNATI, OHIO, A CORPORATION OF OHIO.

SWITCH-STAND.

1,395,865.

Specification of Letters Patent. Patented Nov. 1, 1921.

Application filed July 20, 1921. Serial No. 486,154.

To all whom it may concern:

Be it known that I, CHARLES PARTINGTON, a citizen of the United States, residing at Cincinnati, in the county of Hamilton and 5 State of Ohio, have invented certain new and useful Improvements in Switch-Stands, of which the following is a specification.

This invention relates to switch stands and has for its object the provision of mechanism for throwing a switch which will be compactly arranged and which will operate smoothly and easily. A particular object of 10 the invention is to provide an arrangement and construction of parts which will permit 15 the employment of a straight lever and in which the frictional resistance to the movement of the working parts will be minimized. Another object of the invention is to provide an arrangement by which the 20 movement of the operating lever will be transmitted to the switch-connecting rod without any binding of the parts and without requiring excessive effort by the switchman. Another object of the invention is to 25 provide means whereby the operating lever will be supported in a horizontal plane in either of its positions and in which all the working parts will be protected against an 30 accumulation of dirt or from the entrance of snow or other matter which would tend to interfere with the successful use of the apparatus.

The invention is illustrated in the accompanying drawings, in which—

35 Figure 1 is an elevation of a switch stand embodying my improvements;

Fig. 2 is a bottom plan view of the same;

Fig. 3 is an end elevation thereof;

40 Fig. 4 is a detail partly in end elevation and partly in transverse section;

Fig. 5 is a detail perspective view of the slide;

Fig. 6 is a detail perspective view of another form of slide.

45 In carrying out my invention, I employ a base plate 1 which is adapted to rest upon adjacent railroad ties and bridge the same, the said base plate being constructed at one side with a longitudinal depending portion 2 which serves to prevent stones or other objects being thrown into the space immediately below the base plate or rolling into said space so as to clog the angle lever which acts directly upon the switch-connecting bar. 50

55 The base plate is also formed with a longitudi-

dinal arch or raised portion 3 which constitutes a cover and support for the pivot of the angle lever, and at the ends of the depending portion 2, standards 4 rise from the base plate, the said standards being constructed with shoulders 5 upon their inner edges to limit the throw of the operating lever and support the same in a horizontal position. A cover 6 is secured to the said standards 4 and bridges the upper ends 60 thereof as well as the rear edges of the same so that the slide and the parts directly engaging the same will be housed and protected from the weather and other detrimental elements. Secured in the standards 65 4 and extending longitudinally of the cover or housing 6 are supporting and guide rods 7 upon which is mounted the slide 8. The supporting and guide rods 7 are preferably 70 circular in cross section and are disposed vertically one above the other, the slide 8 being provided with passages 9 therethrough to be fitted upon the said rods so as to slide freely 75 thereon. In the form shown in Figs. 1 to 5, the slide 8 consists of a block having a vertical groove or recess 10 upon its inner side and a transverse groove or recess 11 in its lower end. The groove 11 in the lower end of the slide is engaged by a roller 12 carried by one 80 arm 13 of an angle lever which is pivotally supported by the arched cover or hanger plate 3, the other arm 14 of said lever having one end of the switch-connecting bar 15 pivoted thereto. The angle lever is pivotally mounted upon the lower end of a post 85 or pin 16 which is secured in the plate 3 and depends therefrom, the lever being provided at its angle with hub portions 17 so as to reinforce the lever at its pivot point and also to provide a wide bearing around the pivot 90 pin to counteract any tendency of the lever or the pivot post to bend in the use of the apparatus. Secured upon the plate 3 in the vertical plane of the pivot post 16 is a bracket or standard 18 which is preferably 100 of an inverted U-shaped formation so as to bridge the upper end of the post and thereby protect the same against an accumulation of snow or ice or dirt. Disposed transversely in the upper end of this standard or 105 bracket 18 is a horizontal pivot post 19, upon the inner end of which the operating lever 20 is fulcrumed. The fulcrum of the lever is disposed close to the working end thereof and at its working end the lever car- 110

ries a roller 21 which plays in the vertical groove 10 of the slide. It will be readily noted that the parts described are very compactly arranged and the lever 20 is straight 5 throughout its length so that it may be accommodated in a very narrow space between the standards 4 and the bracket or post 18. When the lever is at rest, it will be supported upon the shoulder 5 of one of the 10 standards 4 and will be thereby maintained in a horizontal plane and it will be readily noted, upon reference to Figs. 1 and 4 particularly, that, when in this position, the pivot or fulcrum of the lever and the point 15 of engagement of the same with the slide are in the same horizontal plane and the point of engagement of the lever with the slide is in the same vertical plane as the point of engagement between the angle lever and the 20 slide so that the parts will be locked against free movement and the switch cannot then be shifted except by the application of force to the power end of the lever 20. When the switch is to be shifted, the lever 20 is swung 25 upwardly over and then downwardly from the position shown in full lines in Fig. 1 to the position shown in dotted lines, and this movement will cause its working end to describe an arc about the pivot 19 downwardly under and upwardly so that the roller or pin 21 carried by the working end of the lever will engage the wall of the vertical groove 10 in the slide and cause the 30 said slide to shift longitudinally upon the guiding and supporting rods 7, reaching the 35 position shown in dotted lines in Fig. 1 as the lever again comes to rest in a horizontal plane. As the slide thus moves longitudinally of the rods 7, one wall of the groove 40 11 in the lower end thereof will act upon the roller or pin 12 carried by the angle lever so as to swing said angle lever about its pivot post 16 and thereby actuate the switch-connecting bar 15 to throw the 45 switch. In the shifted positions of the parts, the point of engagement between the operating lever and the slide will again be in the same vertical plane as the point of engagement between the angle lever and the 50 slide and in the same horizontal plane as the fulcrum of the lever so that any reverse motion applied through the switch bar 15 would have to overcome the dead center of the operating lever in order to move the 55 switch from its set position. Consequently, the switch cannot be shifted except by force applied to the outer end of the operating lever.

In the drawings, I have shown the standards 4 as provided with lateral feet 22 which are permanently united with the base plate 1, as by welding, but if a cheaper construction is desired, the standards may be merely struck up from the base plate. Moreover, in 60 Fig. 6, I have shown another form of slide

which consists merely of a plate 23 doubled upon itself transversely at its center to form the bend 24 and provided at its corners with openings 25 to receive the guide and supporting rods. This form of slide may be 70 produced more cheaply than the slide shown in Fig. 5 and will be found satisfactory upon narrow gage roads employing light 75 rolling stock, but I prefer the form of slide shown in Fig. 5 as it is a more substantial structure and will resist more wear without tending to bind upon the supporting rods.

Having thus described the invention, what is claimed as new is:

1. A switch stand comprising a base plate, 80 a housing on the base plate, a guiding rod disposed longitudinally within the housing, a slide mounted upon said rod, a lever supported upon the base plate, means at the end of the lever to engage said slide and actuate the same, an angle lever supported by and below the base plate and provided at one end with means for engaging the lower end of the slide and receiving motion therefrom, and a switch-connecting bar pivotally 85 attached to the opposite end of the angle lever.

2. In a switch stand, the combination of a supporting structure, a slide mounted within said structure and provided in its inner 95 face with a vertical groove and in its lower end with a transverse horizontal groove, an operating lever fulcrumed upon the supporting structure and provided at its working end with means for engaging the vertical groove in the slide, an angle lever pivotally mounted in the supporting structure and provided at one end with means to engage the groove in the lower end of the slide, and a switch-connecting bar pivoted to the 100 opposite end of the angle lever.

3. In a switch stand, the combination of a base plate, a housing erected upon the base plate along one side edge of the same, an arched hanger plate erected on the base 110 plate parallel with and spaced from the housing, a standard upon the upper side of said hanger plate, a post depending from the hanger plate and having its upper end bridged by the said standard, a pivot post 115 disposed horizontally and transversely in the upper end of said standard, a slide within the housing, an operating lever fulcrumed upon the pivot post in the upper end of said standard and arranged between said standard and the housing for movement in a vertical plane parallel with the housing, means at one end of said lever to engage the slide and actuate the same, an angle lever pivotally 120 mounted upon the lower end of the post depending from the hanger plate, means at one end of said angle lever to engage the slide and receive motion therefrom, and a switch-connecting bar pivotally attached to the opposite end of the angle lever.

4. In a switch stand, the combination of a supporting structure, a slide mounted therein, means for holding the slide to a rectilinear path, a hand lever fulcrumed at 5 one side of the path of the slide for movement in a vertical plane parallel with the path of the slide, means for effecting an operative engagement between the lever and the face of the slide, an angle lever fulcrumed below the hand lever for movement 10 in a horizontal plane, the fulcrum of the angle lever being in the same vertical plane with the fulcrum of the hand lever, means for effecting operative engagement between one end of the angle lever and the lower end 15 of the slide, and a switch bar pivoted to the opposite end of the angle lever.

In testimony whereof I affix my signature.

CHARLES PARTINGTON. [L.S.]
